[57] **CLAIM**

The ornamental design for a chain end interconnecting clasp, as shown and described.

DESCRIPTION

FIG. 1 is a side elevational view of a chain end interconnecting clasp showing my new design, the opposite side being a mirror image and the broken line chain being illustrative of environment only;

FIG. 2 is a side elevational view thereof with a chain hooked on both ends; and

FIG. 3 is a top edge view thereof.
